UNITED STATES PATENT OFFICE.

RUSSELL THAYER, OF PHILADELPHIA, PENNSYLVANIA, ASSIGNOR TO THE PENNSYLVANIA GLOBE GAS LIGHT COMPANY, OF SAME PLACE.

APPARATUS FOR HEATING WATER.

SPECIFICATION forming part of Letters Patent No. 663,107, dated December 4, 1900.

Application filed July 25, 1900. Serial No. 24,830. (No model.)

To all whom it may concern:

Be it known that I, RUSSELL THAYER, a citizen of the United States, residing at Philadelphia, in the county of Philadelphia and 5 State of Pennsylvania, have invented a certain new and useful Apparatus for Heating Water, of which the following is a specification.

The invention relates to apparatus for heating water, and more particularly to water-heaters mainly intended for household uses.

Water-heaters as heretofore constructed and installed have been generally unsatisfactory. Those deriving their heat from 15 kitchen-ranges and the like are expensive in their equipment and from the almost constant attention and repairs they require, and those heated by gas are objectionable in that the heating-surface obtained does not justify 20 the expense of fuel involved.

The primary object of my invention is to provide a simple, efficient, and economic type of water-heater which shall be free from the objections stated.

25 A specific object is to provide a heating plant which shall be comparatively inexpensive in construction and installation and which will heat a given quantity of water in far less time than has been possible heretofore.

A further object is to provide a powerful burner for producing a blue flame from the vapor of kerosene or other heavy oil.

To these and other ends the invention consists in the improved water-heater and in the novel construction, combination, and arrangement of parts thereof, as will be hereinafter described, and pointed out in the claims.

40 The nature, characteristic features, and scope of the invention will be readily understood from the following specification, taken in connection with the accompanying drawings, forming a part hereof, and in which—

45 Figure 1 is an elevation of a water-heating plant embodying features of my invention, showing the general arrangement of stand-boiler, blue-flame water-heater, and oil-supply tank or reservoir. Fig. 2 is a central vertical section through the heater.

Referring to the drawings, A indicates the

stand-boiler; B, the heater; C, the oil-supply tank, and D the burner.

The boiler A is shown supported upon the standard *a* and as being provided with cold-water inlet *b* and outlet *c* and hot-water inlet *d*, connecting with service-pipe *a'*. The heater C communicates with the boiler by pipes *e* and *f*, respectively, connecting with the inlet *b* and outlet *c*.

Referring to Fig. 2, the heater C is preferably shown as consisting of an outer shell *g* and an inner-lying shell *g'*, separated by a dead-air space, which may receive a suitable non-heat-conducting lining *h*. *i* denotes a casting suitably sustained in the top of the heater and having superposed compartments, the upper one *j* constituting a cold-water chamber and having a downwardly-extended bore or passage *k*, threaded to receive the pipe *l*, removably connected with feed-pipe *f*, as by union *m*. The lower or hot-water chamber *n* has a series of pipes *o* extending vertically therefrom and closed at the bottom by a fire-plate *p*, just above the burner. Communication is had between said water-spaces by means of pipes *q*, telescoping the pipes *o*. *r* denotes a suitable cap having the flue-opening *r'*.

The burner D comprises a vaporizing-bowl 80 *s*, having an asbestos lighting-ring *s'*.

t and *t'* are perforated tubes located, respectively, inside and outside of the vaporizing-bowl and constituting a mixing-chamber *u* for the vaporized fuel. The tube *t* may 85 or may not have a sustaining ring or spider *t²* at its top with a central opening for the passage of pipe *l*.

v denotes the drum or outside casing, provided with lugs *v'*, by which it is removably 90 connected to the flange *g²* of the heater, as by means of bolts *g³*.

C denotes the oil-supply, consisting of tank *d'* and bell *d²*, having a ball-valve *d³*, so as to provide a maintained oil-level in the space *w*. 95 The tank *d'* is supported by means of arms *d⁴*, embracing the heater, and is provided with air-vent *d⁵* and oil-outlet *d⁶*. *d⁷* denotes an oil-supply pipe connecting said outlet with the vaporizing-bowl and provided with a 100 check-valve *d⁸*.

It will be obvious to those skilled in the art

to which the invention appertains that modifications may be made in detail without departing from the spirit thereof. Hence I do not limit myself to the precise construction 5 and arrangement hereinabove set forth and illustrated in the accompanying drawings; but,

Having thus described the nature and objects of my invention, what I claim as new, 10 and desire to secure by Letters Patent, is—

1. A water-heater comprising the combination with a boiler, of a heater embodying a shell having superposed hot and cold water spaces, a source of heat below the heater, a 15 feed - water pipe passing up through said source into the heater and connecting the boiler with the cold-water space, nested pipes connecting the hot and cold water spaces, and a connection from the hot-water space to the 20 boiler, substantially as described.

2. A water - heater comprising a double-jacketed casing lined with a non-heat-conducting medium, superposed hot and cold water spaces, a heat source below the heater, a feed-water pipe passing up through said 25 heat source into the heater and connecting with the cold-water space, hot-water flues extending from the hot-water space to near the heat source, pipes connecting said hot and cold water spaces and inclosed within the 30 flues, and an outlet for the hot water, substantially as described.

In testimony whereof I have signed my name in the presence of two subscribing witnesses.

RUSSELL THAYER.
